Jacob Beesley & Edw^r J. Delany, of Philad^e Pa.
Letters Patent No^r 697. Dated Mar. 30. 1855.

The schedule referred to in these Letters Patent and making part of the same.

Mar 697

To all to whom these presents shall come.

Be it known that We, Jacob Beesley, and Edward J. Delaney, of Philadelphia, and State of Pennsylvania, have invented a new design for stoves and that the following is a full, clear, and exact description of the principle or character which distinguishes it from all other things before known and of the usual manner of making, modifying and using the same, reference being had to the accompanying drawings.

Fig. 1. is a view of the side oven door of the stove illustrating the design thereof.

Fig. 2. is a view of the front of the stove with doors attached.

Fig. 3. is a side view of the front illustrating the side view of the front.

Fig. 4. is a view of the back of the stove.

Fig. 5. is a side view of the back of the stove illustrating the design thereof.

These drawings illustrate our design for the Fanny Forrester Stove.

other parts of the stove being plain and ornamented at pleasure.

What we claim as our invention is the design for Fanny Forrester Stoves as herein above illustrated and set forth.
